(57) **CLAIM**

The ornamental design for a table lamp as shown and described.

DESCRIPTION

FIG. 1 is a top perspective view of a table lamp.

FIG. 2 is a bottom perspective view thereof.

FIG. 3 is a front elevational view thereof (rear and both side elevational views are the same).

FIG. 4 is a top plan view thereof; and,

FIG. 5 is a bottom plan view thereof.

The broken lines of equal length in the drawings depict features of the table lamp that form no part of the claimed design.
